UNITED STATES PATENT OFFICE.

JACOB KALTENBACH, OF WILKES-BARRE, PENNSYLVANIA.

DIRECTION-INDICATOR FOR VEHICLES.

1,212,070.

Specification of Letters Patent.

Patented Jan. 9, 1917.

Application filed October 8, 1915. Serial No. 54,849.

To all whom it may concern:

Be it known that I, JACOB KALTENBACH, a subject of the Emperor of Germany, residing at Wilkes-Barre, in the county of Luzerne and State of Pennsylvania, have invented new and useful Improvements in Direction-Indicators for Vehicles, of which the following is a specification.

This invention relates to improvements in direction indicators for vehicles and has particular application to a manually operated direction indicating device.

In carrying out the present invention it is my purpose to provide a direction indicating device which will be found especially useful upon motor vehicles and whereby the driver of the vehicle may notify pedestrians and drivers of other vehicles of the direction in which he is about to steer his vehicle.

It is also my purpose to provide a device of the class described which will embody the desired features of simplicity, efficiency and durability, which may be applied to any type of vehicle quickly and conveniently and which may be easily operated by the driver of the vehicle.

With the above and other objects in view the invention consists in the construction, combination and arrangement of parts hereinafter set forth in and falling within the scope of the claims.

In the accompanying drawing, Figure 1 is a fragmentary top plan view of a motor vehicle equipped with a direction indicating device constructed in accordance with my present invention. Fig. 2 is a view in side elevation of the device removed from the vehicle. Fig. 3 is a horizontal sectional view through the device. Fig. 4 is a vertical sectional view therethrough.

Referring now to the drawings in detail 1 designates a clamp of any suitable or preferred construction adapted to surround the filling nipple of the radiator. Formed integral with the clamp 1 or otherwise secured thereto, and projecting outwardly therefrom is a horizontal casing 2 embodying a bottom wall 3 and a circular side wall 4 and a removable top wall 5 secured to the upper edge of the side wall 4 by means of screws or the like. Mounted in alining openings formed in the bottom and top walls of the casing is a vertical pin 6 and rotatably mounted upon the pin 6 between the top and bottom walls of the casing is a collar 7 formed with an arm 8 projecting outwardly through a slot

9 formed in the side wall 4 of the casing and adapted to work in such slot. Rotatably mounted within alining openings formed in the top and bottom walls respectively of the casing is a vertical shaft 9' having the ends thereof projecting beyond the top and bottom walls of the casing and formed with slots 10 respectively. This shaft 9' is arranged upon one side of the pin 6 and fixed thereto between the top and bottom walls of the casing is a pinion 11 meshing with a curved rack bar 11' carried by the collar 7 and arm 8.

12 designates an indicating hand having the end thereof opposite from the fingers bifurcated as at 13 and this bifurcated end of the hand straddles the casing and the limbs of the bifurcated portion are disposed within the respective slots 10 and suitably fastened therein so that in the rotation of the shaft 9' the hand may be swung. Surrounding the outer end of the pin 6 at one side of the casing is a spring 14 having one extremity fastened to the casing and the other end bearing against the arm 8. Also connected to the outer end of the arm 8 is a wire 15 projecting toward the driver's seat and connected with an operating lever 16 disposed within convenient reach of the driver. Encircling the wire 15 is a protecting tube 17.

In practice the lever 16 is held in a position to maintain the hand 12 pointing straight ahead against the action of the spring 14 and when it is desired to actuate the hand to one side, to indicate the turn, the wire 15 is relieved of the holding influence of the lever 16 and the spring 14 reacts to rotate the arm 8 and rack bar 11 and revolve the pinion 11 and shaft 9' whereby the hand 12 will be swung at right angles to its normal position to indicate the direction in which the driver is about to steer his vehicle. To restore the hand to normal position the wire 15 is pulled under the action of the lever 16 so that the shaft 9' will be revolved in the opposite direction to move the hand to straight ahead position. When it is desired to swing the hand to indicate a turn in the opposite direction, the wire 15 is pulled and the hand swung against the action of the spring 14.

While I have herein shown and described one preferred form of my invention I wish it to be understood that I do not limit or confine myself to the precise details of con-

struction herein described and delineated, but that modifications and variations may be made within the scope of the claim and without departing from the spirit of the 5 invention.

I claim:—
A direction indicating device for vehicles comprising, a casing, a vertical shaft journaled in said casing and having the ends 10 thereof projecting above and below the casing, an indicating hand having the end re-

note from the fingers bifurcated and straddling said casing and having the limbs of the bifurcated portion secured to the projecting ends of said shaft, and means for rotating said shaft to swing said hand. 15

In testimony whereof I affix my signature in presence of two witnesses.

JACOB KALTENBACH.
